(57) **CLAIM**

The ornamental design for an alarm clock kit, as shown and described.

DESCRIPTION

FIG. 1 is a perspective view of an alarm clock body of an alarm clock kit showing our new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of first support feet of the alarm clock kit shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of second support feet of the alarm clock kit shown separately for ease of illustration;

FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of first alarm clock ears of the alarm clock kit shown separately for ease of illustration;

FIG. 26 is another perspective view thereof;

FIG. 27 is a front elevational view thereof;

FIG. 28 is a rear elevational view thereof;

(Continued)

FIG. 29 is a left side elevational view thereof;
 FIG. 30 is a right side elevational view thereof;
 FIG. 31 is a top plan view thereof;
 FIG. 32 is a bottom plan view thereof;
 FIG. 33 is a perspective view of second alarm clock ears of the alarm clock kit shown separately for ease of illustration;
 FIG. 34 is another perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is a top plan view thereof;
 FIG. 40 is a bottom plan view thereof;
 FIG. 41 is a perspective view of third alarm clock ears of the alarm clock kit shown separately for ease of illustration;
 FIG. 42 is another perspective view thereof;
 FIG. 43 is a front elevational view thereof;
 FIG. 44 is a rear elevational view thereof;
 FIG. 45 is a left side elevational view thereof;
 FIG. 46 is a right side elevational view thereof;
 FIG. 47 is a top plan view thereof;
 FIG. 48 is a bottom plan view thereof;
 FIG. 49 is a perspective view where the first support feet and second alarm clock ears are assembled with the alarm clock body;
 FIG. 50 is a perspective view where the first support feet and first alarm clock ears are assembled with the alarm clock body;
 FIG. 51 is a perspective view where the first support feet and third alarm clock ears are assembled with the alarm clock body;
 FIG. 52 is a perspective view where the second support feet and second alarm clock ears are assembled with the alarm clock body;
 FIG. 53 is a perspective view where the second support feet and first alarm clock ears are assembled with the alarm clock body; and,
 FIG. 54 is a perspective view where the second support feet and third alarm clock ears are assembled with the alarm clock body.

The broken lines in the drawings depict portions of the alarm clock kit that form no part of the claimed design.
